Primary Examiner — Kevin Rudzinski*Assistant Examiner* — Kathleen Jones(74) *Attorney, Agent, or Firm* — Kane Kessler, P.C.; Paul E. Szabo(57) **CLAIM**

The ornamental design for a speedloader holder, as shown and described.

DESCRIPTION

FIG. 1 is a perspective view of the speedloader holder. The evenly-spaced broken lines show a speedloader that forms no part of the claimed design. The uneven-spaced broken lines are included to depict the intended alignment of the speedloader and the speedloader holder and form no part of the claimed design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a front elevational view thereof; and,

FIG. 7 is a rear elevational view thereof.

1 Claim, 4 Drawing Sheets(56)
